FENCE POST

Frank W. Meyer, East St. Louis, Ill.

Application July 16, 1942, Serial No. 451,145

10 Claims. (Cl. 256—52)

This invention relates to fence posts; and has special reference to fence posts including a post body adapted to extend into and above the ground, and a fence holding or attaching member adapted to be detachably secured to that portion of the post body that extends above the ground.

An object of the invention is to provide a post comprising a post body having a lower portion adapted to extend into the ground and an upper portion extending above the ground, and a fence holding or attaching member interlocked with that portion of the post that extends above the ground in a manner to prevent displacement in any direction, and lateral extensions rigid or integral with the lower portion of the post that is embedded in the ground and which also are covered in the ground when the post is in use and which function by engagement with the ground to prevent lateral tilting or leaning of the post.

Another object of the invention is to provide a metallic post including a tubular lower portion sealed at its upper end and adapted to be driven or mounted in the ground to support the post for use, an upper portion that is angular in cross-section and which is integrally united with the lower portion and rigidly supported thereby, in combination with a fence attaching and holding member adapted to be interlocked in the angular upper portion of the post and adapted to support the fence structure and, in the case of wires, to stretch and hold the wires under tension.

Another object of the invention is to provide an improved metallic fence post having a lower portion adapted to be extended or driven into the ground and an integral upper portion that is angular in cross-section, and a device adapted to be interlocked with the angular upper portion of the post for supporting the fence structure; and in this construction said device may be either an impenetrable metallic element provided with means for supporting wires, or penetrable so that nails may be driven into it to support suitable fence structure.

Various other objects and advantages will appear from the following description, reference being made to the annexed drawings, in which—

Fig. 1 is a side elevation with parts in section showing that embodiment of the invention including the tubular lower portion of the post having its upper end closed or hermetically sealed.

Fig. 2 is a top plan view of the post shown in Fig. 1, also showing the post proper and the fence holding or attaching member spread apart.

Fig. 3 is an enlarged plan view similar to Fig. 2, showing fence wires attached to the post.

Fig. 4 is a vertical cross-sectional view of the upper portion of the post on the line 4—4 of Fig. 3.

Fig. 5 is a top plan view of a post of modified construction but including an angular upper portion and a fence holding or attaching member nested in the angle of the upper portion for holding fence wires.

Fig. 6 is a vertical sectional view of the upper section of the post on the line 6—6 of Fig. 5.

Fig. 6a is a top plan view of the post shown in Figs. 1 and 2, showing angularly extended fence wire supporting members attached to and projecting above the post proper.

Fig. 6b is a vertical cross-sectional view of this portion of the post on the line 4—4 of Fig. 3.

Fig. 7 is a side elevation of a modified form of post having the upper portion thereof shown in section, the post proper and the fence holding or attaching member being spread apart.

Fig. 8 is a plan view of the post shown in Fig. 7, the two post elements being spread apart.

Fig. 8a is a vertical cross-sectional view of the upper portion of a post like the post shown in Fig. 5 and having attached thereto angularly extended fence wire supporting members.

Fig. 8b is a cross-sectional view on the line 8—8 of Fig. 8a.

Fig. 9 is an elevation showing the attaching side of a post of modified construction having a penetrable fence attaching and supporting member detachably secured thereto.

Fig. 10 is a top plan view of the post shown in Fig. 9.

Fig. 11 is a top plan view of the post elements of Figs. 9 and 10 showing said elements spread apart.

Fig. 12 is a side elevation of the post of Figs. 9, 10 and 11, the upper portion of the post body being in section and the fence supporting or holding member spaced from the post body, as in Fig. 11.

Fig. 13 is a sectional view of the upper portion of the assembled post of Figs. 9 and 10, showing a completed fence.

In one embodiment of the invention, the post body is composed of a section of tubing. It comprises a hollow tubular lower portion adapted to be driven into the ground or otherwise placed and embedded in the ground. Approximately one-half of the upper portion of the post, which is to say that portion of the post body that extends above the ground, is rolled or otherwise

pressed together to form the upper portion of the post body. Preferably, the upper portion of the tube is pressed together to form an outer ply 2 and an inner ply 3, the inner ply 3 comprising that one-half of the tube opposite from the ply 2. Thus a vertical channel is formed in one side of the upper portion of the post above the tubular lower portion 1. The lower end of the inner ply 3 is integrally connected with the wall of the tubular lower portion 1 by a connecting wall 4. The plies 2 and 3 may be hermetically and imperviously sealed by any appropriate hermetic sealing means, as by a weld 5.

A hole is formed in the wall 4, which is left open when the tubular part 1 of the post is driven into the ground in order to permit escape of air from within said tubular part 1. After the tubular part 1 of the post has been driven completely into the ground, as indicated in Fig. 1, the hole in the wall 4 is hermetically closed and sealed by a plug 6 and a weld 7, or otherwise. This substantially prevents withdrawal of the post from the ground without at the same time removing the body of earth or material contained within the post, since withdrawal of the post from the ground without said core of earth or body of material would create a vacuum within the tubular part 1.

A pair of oppositely extended arms 8 of considerable vertical width are rigidly attached to opposite sides of the tubular part 1 of the post by welds 9 or otherwise. These arms extend in the same general direction in which the fence 10 extends, and they function to prevent or resist lateral tilting or leaning of the post. They co-operate directly with the lower portion of the post that is embedded in the ground to prevent or retard such lateral leaning or tilting.

A semi-tubular fence holding or attaching member 11 is provided for cooperation with the upper portion of the post 2-3 to support, hold and tension the fence wires 10. The plies 2-3 have holes 12 with which holes 13 in the member 11 register when said parts are in cooperative relation. The member 11 is provided with a number of bendable fingers or projections 14 adapted to receive thereon and thereby support the wires 10 of the fence. Bolts 15 may be passed through the holes 12 and 13 in order to attach the member 11 to the post proper and complete the fence. Removable and replaceable nuts 16 are provided for the bolts 15. The fasteners 15-16 constitute means for drawing the member 11 forcibly toward the post proper whenever the wires 10 become slack or loose, in order to tighten and tension said wires. In their final positions, the fingers or projections 14 may engage against the ply 3, as shown in Fig. 4, and be bent or clinched about the wires 10.

As shown in Figs. 6a and 6b, the post may be provided with angularly extended wire supporting members attached to and projecting above the post proper. Either of these angularly extended wire supporting members projecting above and laterally beyond the post proper may be used without the other, or both may be used together. As shown, the member 2a is of single-ply thickness, approximately semi-circular in end elevation or in cross-section in conformity with the curvature of the ply 2. This member is angular in cross-section and the lower portion thereof seats and curves against the outer curved surface of the ply 2 while the upper fence wire supporting portion of said member extends therefrom at an angle of about 45°, more or less. This

angular relationship may be varied optionally.

The upper bolt 15 passes through the lower portion of the member 2a and clamps the same rigidly against the ply 2, as shown in Fig. 6b.

- 5 Additional fence wires 10a may be extended across the curved side of and above the member 2a and held rigidly in place by an attaching member 11a having bendable fingers or projections 14a adapted to receive thereon and thereby support the wires 10a. Bolts 15a with nuts 16a analogous to the bolts 15 and nuts 16 pass through members 2a and 11a and constitute releasable means for holding said member 11a in rigid position and for forcing said member toward 10 the member 2a to hold the wires 10a under tension and to tighten them when they become slack or loose. An opening 2b is formed through the lower portion of the member 2a near the angle thereof and above the body of the post 15 proper to permit water and other accumulated material to drain and pass from within said member 2a.

- 20 The other angularly extended wire supporting member projects beyond the opposite side of the post from the member 2a, and comprises a part 11b that is approximately semi-circular in end elevation or in cross-section. The member 11b curves oppositely from the member 2a and may be integrally or otherwise attached to the upper 25 portion of the member 11 as by welding 11c. The upper bolt 15 which holds the member 11 in rigid assembly on the post proper thereby holds the part 11b in rigid assembly. An attaching member 11a having bendable fingers 14a is a duplicate 30 of the member 11b previously described, and is engaged and held in position by bolts 15a and nuts 16a. The member 11b is formed with a hole h near its angle for the discharge of water and other accumulations from said member 11b. 35 Thus, it will be seen that either one or both of the angularly extended wire supporting members 2a and 11b may be used optionally.

- 40 The alternative form of post body is angular in cross-section throughout its length and omits 45 the tubular anchoring portion 1, but includes a pair of oppositely extended arms analogous to the arms 8 and for the same purpose. This alternative form of post comprises a body including 50 a lower portion 17 adapted to be driven or otherwise anchored in the ground and an upper portion 18 extending above the ground to support the fence proper. Each of the two angularly extended sides of the lower portion 17 of this post has an arm 19 integrally or rigidly attached thereto by welds 20 or otherwise. These arms extend generally in the direction in which the fence wires 21 (Fig. 5) extend in order to prevent 55 or resist lateral leaning or tilting of the post after the fence is completed. Holes 22 are formed through the angle of the upper portion 18 of the post and register with similar holes 23 in the angular attaching member 24 when the parts are assembled and the fence is completed. A number of bendable fingers or projections 25 60 are formed integral or rigid with the fence holding and supporting member 24 for engagement with the fence wires 21 to hold and support the same. Bolts 26 pass through the holes 22 and 23 and are equipped with nuts 27 which may be 65 tightened to place the wires 21 under tension. These nuts 27 may be tightened from time to time whenever the wires 21 become slack or loose, in order to stretch and tension them. The member 24 is preferably metallic and substantially 70 impenetrable, and is designed to function as the 75

member 11 to support wires against the post proper, to tension said wires initially, and to be operated to tension and stretch the wires whenever they become slack or loose after completion of the fence.

As shown in Figs. 8a and 8b, the post of Fig. 5 may be provided with one or more angularly extended wire supporting members attached to and projecting above the post proper. Either of these angularly extended wire supporting members projecting above and laterally beyond the post proper may be used without the other, or both may be used together. As shown, the member 18a is angular in end elevation or in cross-section in conformity with the angular formation of the body portion 18. The lower portion of this member engages against the outer angular surface of the post body 18 while the upper fence wire supporting portion of said member extends therefrom at an angle of about 45°, more or less. This angular relationship may be varied optionally. The upper bolt 26 passes through the lower portion of the member 18a and clamps the same against the post body 18, as shown. Additional fence wires 14 may be extended across the upper side of the member 18a and held rigidly in place by an attaching member 24a having bendable fingers or projections 14a adapted to receive thereon and thereby support the wires 14. Bolts 26a with nuts 27a analogous to the bolts 26 and nuts 27 pass through the members 18a and 24a and constitute releasable means for holding said member in rigid position to hold the wires under tension and to tighten them when they become slack or loose. An opening 18b is formed through the lower portion of the member 18a for the discharge of water and other accumulations.

The other angularly extended wire supporting member projects beyond the opposite side of the post from the member 18a, and comprises a part 24b which is angular in end elevation or in cross-section. The member 24b extends oppositely from the member 18a and may be integrally attached by welding or otherwise secured to the upper portion of the member 24. The bolt 26 which holds the member 24 in rigid assembly on the post proper thereby holds the part 24b in rigid assembly. An attaching member 34 having bendable fingers 35 is a duplicate of the attaching member 24a, previously described, and is engaged and held in position by bolts 36 and nuts 37. The member 24b is formed with a hole 24c near its angle for the discharge of water and other accumulations. Thus, it will be seen that either one or both of the angularly extended wire supporting members 14a and 24b may be used optionally.

In the fence of Fig. 1 or the fence of Fig. 7, a penetrable removable and replaceable fence supporting and holding member may be substituted either for the member 11 or the member 24. This penetrable fence holding and attaching member is shown in Figs. 9 to 13, and comprises an elongated member 28 of wood or the like, angular in cross-section, so as to be received within and interlock with the upper portion of the post, and provided with holes 29 adapted to register with the holes 22. Bolts 30 and nuts 31 constitute means for fastening the member 28 to the post proper in the manner of the fasteners 15—16 and 26—27. Longitudinal stringers 32 may be fastened to the outer surfaces of the members 28 by nails 33 driven through said stringers and into the member 28, or by other fastening means. In this form of post, the mem-

bers 28 may be removed and replaced from time to time since they may not last as long as the post proper, and it may be desirable for one purpose or another to make repairs and substitutions.

5 This may easily be done. In all forms of the post shown, the fence holding and attaching members 11, 24 and 28 are wholly above the ground, as shown.

From the foregoing, it is apparent that this 10 invention economically and satisfactorily attains all of its intended objects and purposes. It is possible that the invention may be varied otherwise within the scope of equivalent limits without departure from the nature and principle 15 thereof. I contemplate such variations as may be found desirable.

I claim:

1. A fence post composed of a tubular lower portion adapted to be embedded in the ground 20 and having a closed upper end, an upper portion of the post integrally united with said tubular lower portion and having a vertical channel along one side thereof, a fence stretching and holding or attaching member arranged to extend longitudinally within said channel in said upper portion, means for supporting fence elements between said upper portion of said post and said attaching member, leaving said fence elements extending angularly across said attaching member 25 and within said channel in said upper portion, and means for drawing said attaching member toward and securing said member to said upper portion of said post.

2. A metallic fence post composed of a tubular lower portion to be embedded in the ground and an angular upper portion extending above the ground to support the fence and having a vertical channel along one side thereof, a metallic fence holding or attaching member extending 30 longitudinally within said channel in said upper portion, means integral with said member for engaging and supporting fence elements extending between said upper portion and said member and angularly across said member within said channel in said upper portion, and releasable devices for forcibly drawing said member toward said upper portion and within said channel to tension and tighten the fence elements and for attaching said member to said upper portion.

3. A metallic fence post comprising a lower portion adapted to be embedded in the ground and an angular upper portion above the ground for supporting fence structure extending transversely of the angle of said upper portion, arms 35 rigid with said lower portion and extending in opposite directions and parallel with the fence for preventing lateral tilting or leaning of the post, a penetrable nail receiving member seated within the angle of the upper portion of said post above the ground, releasable devices holding said member from longitudinal and also from lateral displacement, fence structure extending across the exposed side of said member, and means embedded in said member securing the fence structure thereto.

4. A metallic fence post comprising a tubular lower portion adapted to be embedded in the ground and having its upper end hermetically sealed and an upper portion provided with a vertical channel along one side thereof, an attaching member mounted within said channel in said upper portion, releasable devices rigidly securing said attaching member to said upper portion and preventing both lateral and longitudinal displacement of said member, and fence structure wholly

supported by the exposed side of said attaching member.

5. A fence post comprising a lower end portion adapted to be embedded in the ground and an upper end portion projecting above the ground for supporting the fence, a fence holding or attaching member rigidly secured to said portion of said post that extends above the ground for holding the fence in rigid relationship on the post, an angularly extended wire supporting member attached to and projecting above said post laterally from the direction in which the fence extends across the post, and two oppositely extended arms of relatively considerable vertical width attached to opposite sides of said lower end portion adapted to be embedded in the ground with said lower end portion and extending generally in the direction of and parallel with the fence for preventing lateral tilting and leaning of the post and the fence.

6. A fence post comprising a lower end portion adapted to be embedded in the ground and an angular upper end projecting above the ground for supporting the fence, a fence holding or attaching member nested within the angle of said portion of said post that extends above the ground for holding the fence in rigid relationship on the post, releasable devices for attaching said member to said upper end portion, a supporting member projecting above and laterally from said post and the fence attached thereto, and means for holding said supporting member in rigid connection with said upper end portion of the post.

7. A fence post comprising a lower end portion adapted to be embedded in the ground and an angular upper end portion projecting above the ground for supporting the fence, a fence holding or attaching member rigidly secured within the angle of said portion of said post that extends above the ground for holding the fence in rigid relationship on the post, diverging supporting members projecting above and laterally from said post and the fence attached thereto, means for holding said supporting members rigidly attached to said upper end portions in positions diverging angularly upwardly and laterally from the post and beyond the sides of the post, and two oppositely extended arms of relatively considerable vertical width attached to opposite sides of said lower end portion adapted to be embedded in the ground with said lower end portion and extending generally in the direction of and parallel with the fence for preventing lateral tilting and leaning of the post and the fence.

8. A fence post comprising a lower end portion adapted to be embedded in the ground and an upper end portion rising from integral connection with said lower end portion and having a

channel along one side thereof from its upper end to said lower end portion, a vertically elongated fence holding or attaching member mounted within said channel, fasteners extending through said member and through said upper end portion of the post for holding said member rigidly within said channel, and projections attached to and supported by said member and located within said channel for receiving and supporting fence structure extending between said member and said upper end portion of said post.

9. A fence post comprising a lower end portion adapted to be embedded in the ground and an upper end portion rising from integral connection with said lower end portion and having a channel along one side thereof from its upper end to said lower end portion and having a vertical series of holes approximately midway between the side edges thereof, a vertically elongated fence holding or attaching member located within said channel and having a vertical series of holes complementary to said holes in said upper end portion, projections attached to and supported by said member and located within said channel for receiving and supporting fence structure extending between said member and said upper end portion of said post across said channel, and devices extending through said holes for forcibly drawing said member into said channel and thereby tightening fence structure extending across said channel between said member and said upper end portion.

10. A fence post comprising a lower end portion adapted to be extended into the ground and an upper end portion rising from integral connection therewith and having a channel along one vertical side thereof from its upper end to said lower end portion and having a vertical series of holes therethrough approximately midway between the side edges thereof, a vertically elongated fence holding or attaching member located within said channel and having a vertical series of holes corresponding to said vertical series of holes through said upper end portion, fasteners extending through said holes in said upper end portion and said member, detachable parts engaging said fasteners and holding said member rigidly in said channel, two separate oppositely extended vertically wide arms having their inner ends spaced apart, means attaching said inner ends of said respective arms to the outer side of said lower end portion and leaving said channel open and unobstructed by any part of said arms, and means attached directly to said member and unattached to said upper end portion for supporting fence structure.

FRANK W. MEYER.
